[57] ABSTRACT

A prefabricated multi-rack stacker system comprising double row multi-stacker shelves including support members each having at its lower end a base being adjustable to vary height of the support member in order to allow the system to be installed at a desired location which may be uneven in its floor surface. The support member is mounted on the base in a swingable manner more finely meet the above requirement. The system further comprising a plurality of detachable upper connecting members, a plurality of lower connecting members, an upper rail detachably mounted onto the upper connecting members and serves to guide and support upper end of an accumulation conveyor in a movable manner, and a detachably mounted lower rail, which serves to guide and support the lower end of the conveyor. The system is made in a prefabricated manner so that the installation at any desired location can be made ease. The system is further equipped with various aspects to improve the operation and function.

MULTI-RACK STACKER SYSTEM

BACKGROUND OF THE INVENTION

1. Field of the Invention

The present invention relates to a multi-rack stacker system equipped with an accumulation conveyor for storing loads, such as various products, semi-product, materials, etc. in a warehouse, factor or the like.

2. Description of the Prior Art

Several types of multi-rack stacker systems are known. In one of such prior devices, the conveyor is supported by lower rails secured at lower side of the support members of the racks. In another embodiment of the prior arts, the lower rail supporting the conveyor is fixed onto the floor surface independently from the support members of the multi-rack stacker shelves arranged at both sides of the rails.

In such conventional devices, multi-rack stacker shelves installed at both sides of the stacker system are independently fixed on the floor surface with each other and with respect to the lower portion of the conveyor. Accordingly, in order to install such a stacker system it is necessary to finely finish the floor surface level in order to accurately mount the independent base of the supporting members of the multi-rack stacker shelves and also the base of the conveyor. It is often troublesome to obtain an accurate adjustment for the relative position of the shelves and the conveyor in case the multi-rack stacker shelves have a considerable longitudinal length, since it is usual that the floor of a warehouse or factory is uneven and in case if a part of a plurality of supports is not fixedly secured to match the floor, the load is concentrated to a part of supporting members so that the supporting strength of the shelf may become insufficient and the shelf may be deformed by the stress imposed to a particular supporting member.

In such conventional devices, furthermore, it is required to enlarge the cross-sectional area of the longitudinal frames of the accumulation conveyor in order to maintain its rigidity of the frame sufficient to endure its length determined by a lifting height of the conveyor. The longitudinal frame may be somewhat enlarged in cross-section in the conveyor travelling direction, however, it cannot be enlarged in a direction normal to the conveyor travelling direction because power supply cables and counterweights occupy the spaces on both sides of the frame. Owing to such a limitation in space, a thickness of metal plates constituting the frame must be increased in order to improve the rigidity of the frame, which results in a heavy frame construction and increases the cost of the system.

In another conventional devices, for the purpose of detecting the stopping position of a carriage of an accumulation conveyor, limit switches are fixed to the carriage and strikers adapted to act on the limit switches are directly fixed to the longitudinal frames of the conveyor or fixed to striker rails connected to the frames. With the arrangement, in the event of a number of limit switches and strikers, a severe working tolerance of parts and a precise installing of the device are essentially required to obtain stable operation of the switches. If the tolerance and precision do not meet the requirement, each limit switch would unstably operate which gives rise to malfunction of the accumulation conveyor.

In the prior art, moreover, locations where the strikers are mounted are determined to match the size of loads to be treated requested for the system, which makes the system a poor flexibility on sizes of loads to be treated.

In another conventional devices, an accumulation conveyor is provided with an extensible and retractable fork consisting of upper, lower and intermediate forks, between which are arranged rollers at the ends and mid portion of the intermediate fork for slidably supporting the upper fork and at the ends and mid portion of the lower fork for slidably supporting the intermediate fork. In the arrangement, when the fork extends while a load is on the front end of the upper fork, an upwardly directing force exerts on the mid portion rollers and a downwardly directing force exerts on the front end rollers which is considerably larger than the upwardly directing force. Accordingly, it is required to increase the rigidity of roller mounting at the ends of the forks. Such a requirement would unexpectedly increase the overall height of the extensible and retractable fork.

In still another conventional devices, a detecting rod having a rack fixed thereto in mesh with a pinion for driving the rod is provided at its front end with a push-button switch for detecting loads. If the push-button switch at the front end of the rod hits a pallet, the switch provides a signal indicating the presence of the pallet and a further signal causing the rod to retract. If there is no pallet, the rod advances to its extreme position where another switch provides a signal indicating the absence of the pallet. Such a conventional arrangement is complicated in construction and is likely to cause a failure in operation resulting from the fact that the front end of the detecting rod is subjected to an excess load due to the weight of the pushbutton switch and cables for the push-button switch are moved on a floor when travelling.

In another conventional stacker system, inner and outer support members of multi-rack stacker shelves are arranged in alignment with each other, respectively, and stack members are mounted on the support members, on which stocks or pallets are loaded by means of an extensible and retractable fork of an accumulation conveyor. In the arrangement, however, there is a disadvantage in that the distance between the end-most inner and outer support members is the same as the width of the whole stacker shelves so that the stocks cannot be loaded or unloaded in the longitudinal direction, unless unduly limiting the width of the stocks. Accordingly, the width of the stocks must be limited to a lesser dimension for the purpose of enabling the stocks to be loaded or unloaded in the longitudinal direction.

In further conventional stacker system, four positional signals from a carriage are transmitted via a controlling circuit to a control panel from which instructions are transmitted via a controlling circuit to a carriage up-down driving motor and to a fork operating motor. In such an arrangement, the control panel and controlling circuits are complicated in construction and provide greater difficulty in maintenance and inspection which makes the operation of the system expensive.

In still further conventional stacker system, a fork of an accumulation conveyor is driven by means of a motor energized by pushing a push-button and the movement of the fork closes a limit switch to keep the

motor energized even if the push-button is released. In such conventional fork controlling circuit, however, there have been inconveniences in that the push-button must be held by hand until the limit switch is operated by the movement of the fork from its neutral position so that the controlling is troublesome.

In another conventional stacker system, an accumulation conveyor stands still at the unloaded shelf location after stacks have been loaded, and when the conveyor is desired to return back to a station the conveyor location must be compared with the station address in the operation circuit and by the result of this operation the conveyor is moved. With such a conventional system, the operation circuit must make subtraction operation so that the construction of such subtraction operation circuit becomes complicated.

In still another conventional stacker system, an automatic control panel including an operation circuit and a carriage control circuit are constructed in separate units in which the carriage is included, and the automatic control panel is provided with a test device which has not equivalent switches corresponding to contacts of the limit switches provided at the carriage. Such a test device cannot test the controlling circuit and the carriage.

SUMMARY OF THE INVENTION

The present invention is to provide a multi-rack stacker system made in a prefabricated manner to solve the abovementioned inconveniences and furthermore equipped with various novel aspects.

In one aspect the invention, provides a multi-rack stacker system equipped with an accumulation conveyor comprising multi-rack stacker shelves arranged in two rows and at lower portion of each support member thereof a base is fixed in a manner height adjustable and universally movable in any direction, the multi-rack stacker shelves are provided at the upper and lower ends with a number of upper connecting members and a number of lower connecting members detachably arranged spaced apart at an interval in the longitudinal direction of the multi-rack stacker shelves, upper end portion of the accumulation conveyor is supported in freely running manner by an upper rail detachably fixed at the center of the upper connecting members, and lower end portion of the accumulation conveyor is supported in a freely running manner by a lower rail detachably fixed at the center of the lower connecting members.

In another aspect the invention, provides a multi-rack stacker system equipped with an accumulation conveyor, wherein said upper rail is I-shaped in cross-section, on the lower flange of which are arranged upper rollers of the upper end of said accumulation conveyor one at each side of the web of the upper rail, and said lower rail is inwardly flanged, open bottomed channel-shaped in cross-section and is firmly fixed to the lower connecting members by means of clamp members and screw threaded members and lower rollers are arranged one at each side of the lower rail in guiding contact with the vertical webs of the rail and are rotatably supported on the lower end of the accumulation conveyor by vertical shafts.

In further aspect the present invention, provides a multi-rack stacker system equipped with an accumulation conveyor, wherein said base is provided with height adjusting means comprising a male screw

adapted to be screwed into a female screw threaded fitting fixed to the lower end of said each support member and a nut adapted to be rotated by a wrench or the like rotary tool.

5 In another aspect the invention, provides a multi-rack stacker system equipped with an accumulation conveyor, wherein said base is hemispherical which is provided at its periphery with a flange and is formed at its center with an opening loosely receiving the smaller 10 diameter portion of said height adjusting means such that said base is universally movable about the portion in any direction.

In further aspect the invention, provides a multi-rack 15 stacker system equipped with an accumulation conveyor, wherein said base is hemispherical which is formed at its center with a hemispherical cavity receiving a hemispherical head of said height adjusting means abutting thereagainst, said base being provided with a ring fixed to the outer end of said cavity for preventing 20 the loss of the base assembly.

In another aspect the present invention, provides a multi-rack stacker system equipped with an accumulation conveyor, wherein said accumulation conveyor comprises a carriage lifting along guide rails mounted 25 on longitudinal frames each consisting of a box-shaped main body elongated in the carriage travelling direction and reinforcing members of box-shaped in cross-section arranged on and fixed to the end of the main body opposite to said guide rail, said members located 30 one on each side of said main body.

In a still further aspect the invention, provides a multi-rack stacker system equipped with an accumulation conveyor, wherein a reinforcing plate in said main body and webs of the member are made of a single plate, and 35 an end plate and webs of the member on the end of the main body opposite to the guide rail are also made of a single plate, the metal plates of the longitudinal frame being connected with each other by means of welding, and in the spaces within the main body and reinforcing 40 member are accommodated reinforcing spacer plates fixed by welding at intervals along a longitudinal direction of the frame.

In another aspect the invention, provides a multi-rack 45 stacker system equipped with an accumulation conveyor, wherein webs connecting end plates of the main body are made of single plates, respectively, between which, if desired, a reinforcing plate is secured to the webs intermediate the ends thereof.

In still another aspect the invention, provides a multi-rack stacker system equipped with an accumulation conveyor, wherein an end plate of the main body and webs of the reinforcing member are formed in one 50 plate integral with each other.

In other aspect the invention, provides a multi-rack 55 stacker system equipped with an accumulation conveyor, wherein a switch support plate is pivotally mounted at its end on said carriage of the accumulation conveyor by means of a horizontal pivot axis, with the other end of which plate is engaged a spring urging the 60 plate toward a striker rail of said conveyor, on the outer surface of which support plate are mounted limit switches and guide means, and to said striker rail is fixed a striker support plate to which are fixed strikers actuating said switches and guide member in supportingly contact with said guide means.

In another aspect the invention, provides a multi-rack 65 stacker system equipped with an accumulation

conveyor, wherein to said carriage is fixed support members, through each of which passes a screw threaded portion 55 of a support rod 54 having an adjusting nut 56, said spring being coiled about said support rod and adapted to be compressed between the upper end of the switch support plate and the support member, thereby adjusting the force of the spring.

In another aspect the invention, provides the system wherein a roller or a slide shoe is used as guide means or a roller is used as a guide member and a rod-like member is used as guide means.

In another aspect the invention, provides a multi-rack stacker system equipped with an accumulation conveyor, wherein said striker rail is formed with a number of mounting apertures in a row at a short distance interval, and said striker support plate are formed with vertically elongated holes which serve to secure said striker support plates to said striker rail adjustably in height.

In another aspect the invention, provides a multi-rack stacker system equipped with an accumulation conveyor, wherein said accumulation conveyor is provided with an extensible and retractable fork mounted thereon, including a lower fork, an upper fork and an intermediate fork, and said extensible and retractable fork comprises lower flat plate-like restraining bearings between the mid portion of said lower fork and said intermediate fork for preventing said intermediate fork from raising away from said lower fork, flat plate-like bearings at the contact portion between the end of said lower fork and said intermediate fork for supporting load, upper flat plate-like restraining bearings between the mid portion of said intermediate fork and said upper fork for preventing said upper fork from raising away from the intermediate fork, and flat plate-like bearings at the contact portion between the end of said intermediate fork and said upper fork for supporting load.

In still another aspect the invention, provides a multi-rack stacker system equipped with an accumulation conveyor, wherein said fork further comprises advancing and retracting pulleys provided at the front and rear ends of said intermediate fork, an advancing rope extending around the advancing pulley, the ends of which are fixed to the rear ends of the upper and lower forks, respectively, and a retracting rope extending around the retracting pulley, the ends of which are fixed to the front ends of the upper and lower forks.

In another aspect the invention, provides a multi-rack stacker system equipped with an accumulation conveyor, wherein said system is provided with detecting means for detecting loading pallets, the casing of which is fixed to the carriage of the system, to the rear end of which casing is fixed a motor of which shaft is connected through a sliding coupling to the rear end of a driving shaft formed at its front end with a male screw on which is threadably engaged a detecting shaft slidably fitted in said casing and a bearing is rotatably fitted in place on said driving shaft, against the outer surface of which bearing abut holding members, said bearing being provided with a switch operating finger fixed thereto in opposition to a control switch controlling the operation of said motor.

In another aspect the present invention, provides a multi-rack stacker system equipped with an accumulation conveyor, wherein said holding members for said bearing are urged against said bearing by means of

springs the force of which are adjustable by adjusting screws screwed in the outer portion of holding tubes in opposition to the holding members, thereby adjusting the force of the holding members restraining the axial movement of the driving shaft.

In another aspect the invention, provides a multi-rack stacker system equipped with an accumulation conveyor, wherein a distance between the endmost inner and outer support members of said shelves is larger than a distance between the other inner and outer support members, thereby stocks can be loaded or unloaded in the longitudinal direction as well as the lateral direction.

In another aspect the invention, provides a multi-rack stacker system equipped with an accumulation conveyor, wherein the endmost outer support members of said shelves are arranged at a wider distance to each other than that of the other outer support members so that the distance between the endmost inner and outer support members is larger than the distance between the other inner and outer support members and than the width of stocks.

In another aspect the invention, provides a multi-rack stacker system equipped with an accumulation conveyor, wherein the endmost inner support members are arranged closer to each other than in the other support members so that the distance D_1 between the endmost inner and outer support members is larger than the distance D_2 between the other inner and outer support members, thereby stocks can be loaded or unloaded in the longitudinal direction as well as the lateral direction, and the width of the portion of the accumulation conveyor passing through between the endmost inner support members is less than the width of the fork.

In another aspect the invention, provides a multi-rack stacker system equipped with an accumulation conveyor, wherein said accumulation conveyor including an automatic control panel having an operation circuit, a controlling circuit and carriage, said controlling circuit comprises a fork controlling circuit consisting of a first circuit responsive to instructions of "UP CARRIAGE," "DOWN CARRIAGE," "FORK RIGHT" and "FORK LEFT" from automatic control panel and a second circuit for controlling one cycle operation of said fork started by an operation of a relay contact included in said first circuit.

In still another aspect the invention, provides a multi-rack stacker system equipped with an accumulation conveyor, wherein said accumulation conveyor including a fork controlling circuit, said circuit comprises a switch-over contact, a limit switch indicating fork extremity, a limit switch indicating the predetermined positions of said fork, motor interlock switch and field coil of the motor connected in series, and further comprises a timer release contact connected in parallel with said limit switch indicating the predetermined positions of said fork, said contact being adapted to be opened by a timing device.

In another aspect the invention, provides a multi-rack stacker system equipped with an accumulation conveyor, wherein said accumulation conveyor including an automatic control panel having an operation circuit, a controlling circuit and a carriage, said operation circuit is made of addition circuit only, and said carriage is provided with signalling means to send out working completion signal which provides an instruc-

tion from said automatic control panel to a station, which instruction is directly given to said controlling circuit without using any operation circuit, thereby said carriage and accumulation conveyor return to the station automatically with the aid of limit switches included in the controlling circuit and the carriage.

In another aspect the invention, provides a multi-rack stacker system equipped with an accumulation conveyor, wherein said accumulation conveyor including an automatic control panel having test panel device and operation circuit, a controlling circuit and a carriage, said accumulation conveyor comprises accumulation conveyor control means having portions adapted to be connected with a testing circuit and switches provided on said test panel device, and a test device separate from said automatic control panel.

BRIEF DESCRIPTION OF THE DRAWINGS

FIGS. 1 and 2 show front views of base portion of the conventional multi-rack stacker shelves and the accumulation conveyor;

FIGS. 3 to 11 show one embodiment of the present invention, in which:

DESCRIPTION OF PREFERRED EMBODIMENTS

As the conventional multi-rack stacker system equipped with an accumulation conveyor, it is known a system as shown in FIG. 1, which system comprises lower rails 9 fixed at opposite side surfaces of the multi-rack stacker shelves 1' arranged in 2 rows and the lower rollers 11 fixed to the support arm 10 of the accumulation conveyor 7' are engaged to the side surfaces of the lower rails 9, and also a system as shown in FIG. 2, which comprises a lower rail 12 fixed on the floor independently from the multi-rack stacker shelves, and the lower rollers 13 fixed at lower end portion of the accumulation conveyor are engaged with both side surfaces of the lower rail 12.

However, in either of the above systems, the location of the shelf mounted on the floor and the location of the lower end of the accumulation conveyor are adjusted independently from each other so that the installation of the system to obtain an accurate alignment for the relative position of the both elements is difficult and moreover there has been a disadvantage in that the

60
65

relative alignment tends to vary along the longitudinal position of the system. More especially, in a system as shown in FIG. 2, the floor should be reformed for mounting the lower rail 12 so that the installation for obtaining accurate relative dimension of the multi-rack stacker shelves 1' and the lower rail 12 is very difficult.

On the other hand, it is usual that there are some unevenness of the floor surface 14 of the warehouse or a factory so that a part of supporting members 2' of the multi-rack stacker shelves tend to have clearance between the floor surface 14, in which case the multi-rack stacker shelves 7' can only be supported unstably and also the load is concentrated to a particular part of the supporting members so that the strength of the multi-rack stacker shelves may be decreased and moreover it is possible that an automatic running of the accumulation conveyor might be affected by lower deformation of the shelves at mounting of the storing load to a shelf portion where the supporting member 2' has a clearance with the floor surface 14.

FIGS. 3 to 11 illustrate one embodiment of the multi-rack stacker system of which shelves are arranged in two rows and the accumulation conveyor mounted thereon assembled according to the present invention. Referring to FIG. 3, the self-standing multi-rack stacker shelves 1 arranged in two rows parallel to each other comprise support member 2, to each of which is fixed at its lower end a female screw threaded fitting 15 into which is screwed a male screw 18 of height adjusting means 17 having a nut 16 adapted to be rotated by a wrench or the like rotary tool. The height adjusting means 17 is provided at its lower end with a smaller diameter portion 19 loosely fitted within a center of a hemispherical base 3 having at its periphery a flange 20 such that the base 3 is universally movable about the portion 19 in any direction. To the bottom surface of the flange 20 is fixed a buffer ring 22 which is made of elastic material such as rubber and serves to prevent the slip of the base on a floor.

In order to bring the base 3 associated with each support member 2 into intimate contact with a floor surface 14, the height adjusting means 17 is rotatively adjusted to change the height of the support member 2. The adjustment of the height adjusting means 17 can bring the support member into rigid contact with the floor surface in stable condition, even the floor surface is slightly wrinkled or inclined, because of the universality movability of the base 3.

Each multi-rack stacker shelf 1 is provided at its upper and lower ends with a number of upper and lower metallic connecting members 4 and 5 which are arranged spaced apart at an interval in the longitudinal direction of the multi-rack stacker system. The upper and lower connecting members 4 and 5 are detachably connected at their ends to the support members 2 with bolts 23 as is more clearly shown in FIGS. 5 and 6 so that the multi-rack stackers 1 in two rows are held at a predetermined distance over their total length.

A metallic upper rail 6 of an I-shaped cross-section extends along the center of the upper connecting members 4 and detachably connected to the upper connecting members by means of bolts 25 passing through an upper flange 24 of the rail 6 as shown in FIG. 5. Upper rollers 27 mounted on the upper end of the accumulation conveyor 7 are arranged on a lower flange 26 of the upper rail 6 one at each side of the web of the upper rail 6.

A lower rail 8 inwardly flanged of open bottomed channel-shaped cross-section extends along the centers of the lower connecting members 5 and is provided therein with clamp members 28 which serve to firmly fix the lower rail in place to the lower connecting members 5 by means of bolts 29 passing through the clamp members 28 and the lower members 5 as shown in FIG. 7. Lower rollers 30 arranged one at each side of the lower rail 8 are rotatably supported on the lower end of the accumulation conveyor 7 by vertical shafts 31 as shown in FIG. 6.

Referring to FIG. 11 showing another embodiment of mounting of the base, a base 3 is formed in its upper center portion with a hemispherical cavity 32 within which is fitted a hemispherical lower surface 33 of height adjusting means 17 and the base 3 is provided on its upper end with a ring 34 fixed thereto for preventing the loss of the base assembly. With the exception of the configuration, the other construction of the base 3 is similar to that shown in FIG. 9.

Although FIGS. 3 to 6 illustrate the hanging type accumulation conveyor having drive means 21 for travelling at its upper portion, an upstanding accumulation conveyor having drive means for travelling at its lower portion may be used as an alternative.

Any construction other than illustrated in the drawings as the base and its mounting may be employed if the height of the base can suitably be adjusted and the base is universally movable. Any cross-section of the upper and lower rails 6 and 8 other than illustrated in the drawings may be used. In installing the two rows of multi-rack stacker shelves, more accurate and rapid erection could be accomplished at a place where to be installed by connecting with bolts and nuts respective members which had been prefabricated in a factory.

FIGS. 12 to 15 illustrate embodiments of the accumulation conveyor. Referring to FIGS. 12 and 13, a box-shaped main body 36 of a longitudinal frame 35 of the accumulation conveyor is of a rectangular cross-section elongated in a conveyor travelling direction, at one end of which a guide rail 38 is fixed to an end plate 37 and at the other end a reinforcing member 39 is fixed integral with the main body 36.

A reinforcing plate 40 in the main body and webs 41 of the member 39 are made of a single plate, respectively, and an end plate 42 and webs 43 of the member 39 on the end of the main body opposite to the guide rail 38 are also made of a single plate. The metal plates of the longitudinal frame 35 are connected with each other by means of welding.

In the spaces within the main body 36 and reinforcing member 39 are accommodated reinforcing spacer plates 44, 45 and 46 fixed by welding at intervals along a longitudinal direction of the frame 35. A guide wheel 48 is mounted on a carriage 47 facing to the guide rail 38.

Referring to FIG. 14, webs 49 connecting end plates 37 and 42 of the main body 36 are made of single plates, respectively, between which, if desired, a reinforcing plate 50 is secured to the webs 49 intermediate the ends thereof.

The main body 36 in FIG. 15 is similar to that in FIG. 14 with the exception that an end plate 42 of the main body 36 and webs 43 of the reinforcing member 39 are formed in one plate integral with each other.

As can be seen from FIGS. 12 to 15, the box-shaped main body 36 of the longitudinal frame 35 is elongated

in cross-section in the conveyor travelling direction and the reinforcing member 39 of rectangular cross-section is fixed to the end of the main body 36 opposite to the guide rail 38 as shown in the drawings. Such an arrangement provides spaces to arrange electric feeder cables and counterweights and ensures that relatively thinner metal plates are used to fabricate easily and inexpensively the light weight longitudinal frame 35 of high rigidity.

FIGS. 16 to 19 illustrate one embodiment of mounting of a switch support plate and a striker support plate of the accumulation conveyor. The switch support plate 51 is pivotally secured at its lower end to a carriage 47 of the accumulation conveyor with a horizontal pivot axis 52. The carriage 47 is provided at its ends with support members 53 fixed thereto, through each of which passes a screw threaded portion 55 of a support rod 54 having an adjusting nut 56 as shown in FIG. 18.

The support rod 54 passes through the upper end of the switch support plate 51 and is provided at its end opposite to the threaded portion 55 with a stopper 57 limiting the swing of the switch support plate 51. A spring 58 is coiled about the support rod 54 and adapted to be compressed between the upper end of the switch support plate 51 and the support member 53 fixed to the carriage 47.

The switch support plate 51 is provided on its outer side with guide means 59 comprising a roller rotatably secured thereto, on both sides of which are fixed a plurality of limit switches 60 as shown in FIG. 19.

Referring to FIG. 17, a vertical striker rail 61 is fixed to the vertical frame 35 of the conveyor through connecting members 100 and is formed with a number of mounting apertures 62 in a row at a short distance interval (for example 50 mm). A striker support plate 63 are arranged along the striker rail 61 at an interval and are formed with vertically elongated holes 64 as shown in FIG. 18 which serve to secure the striker support plates 63 to the striker rail 61 adjustably in height by means of bolts 65 passing through the elongated holes 64 and the mounting apertures 62 of the rail 61.

To the striker support plate 63 are fixed strikers (switch actuating elements) 66 corresponding to the limit switches 60 and guide members 67 corresponding to the guide means 59 each of which is vertically movable in contact with the guide member 67 while being urged by the force of the spring 58 such that the distance between each limit switch 60 and the striker 66 is held at a constant value.

In the embodiment of FIGS. 16 to 19, the roller is used as guide means 59 and the switch support plate 51 is pivoted at its lower end to the carriage 47 and urged at its upper end towards the striker rail 61 by means of the spring 58. As an alternative, a slide shoe may be used instead of the roller. A roller is used as a guide member while a rod-like member may be used as guide means. The upper end of the switch support plate 51 may be pivotally mounted on the carriage 47 and the lower end of the plate 51 may be urged towards the rail 61.

In the arrangement shown in FIGS. 16 to 19, when the limit switches of the carriage 47 ascending or descending along the longitudinal frame pass via the strikers of the rail 61, the guide means 59 of the switch support plate 51 is urged against the guide member 67 of the striker support plate 63 to keep constant the dis-

tance between the plates 51 and 63 which ensures the stable and accurate operation of the each limit switch 60 to prevent any malfunctioning of the accumulation conveyor.

As there are a number of mounting apertures 62 in the rail 61 and the elongated holes 64 in the striker support plate 63, the support plate 63 can be mounted at a desired level by means of the bolts 65 passing through the selected apertures 62 and finely adjusted in height by the sliding movement of the support plate 63 relative to the bolts 65, whereby the height of the striker support plate 63 can be adapted to the variety in size of stokes without individual adjustments, and the position where the carriage should stop can easily and accurately be adjusted in the factory.

FIGS. 20 to 24 illustrate one embodiment of an extensible and retractable fork for pallet mounted on the carriage 47. An open-topped channel-shaped lower fork 68 is fixed to the carriage 47 and is provided on its side plates 69 with lower support blocks 70 intermediate the ends thereof. Square shafts 71 are securely fitted within square apertures 72 in the side plates 69 by means of adhesives or spot welding. Flat plate-like restraining bearings 73 of a low coefficient of friction are fixed to the bottom surfaces of the lower support blocks 70 and abut against the upper surfaces of lower flanges 75 of an intermediate fork 74 to serve to prevent the rear portion of the intermediate fork 74 from being raised when the fork 74 has moved forwards and extended beyond the end of the lower fork 68 to support a load on its extended end.

Flat plate-like bearings 76 and 77 for supporting load are fixed to the horizontal portion of the lower fork 68 at the ends and intermediate positions therebetween.

An open-bottomed channel-shaped upper fork 78 is provided on its side plates 79 with upper support blocks 80 intermediate the ends thereof. Square shafts 81 are fixed to the blocks 80 and securely fitted within square apertures 82 in the side plates 79 by means of adhesives or spot welding.

Flat plate-like restraining bearings 83 of a low coefficient of friction are fixed to the upper surfaces of the upper support blocks 80 and abut against the bottom surfaces of the upper flange 84 of the intermediate fork 74 to the upper surface of which are fixed flat plate-like bearings 85 and 86 for supporting load at the ends and intermediate positions thereof, whereby preventing the rear portion of the upper fork 78 from being raised when the fork 78 has moved forwards and extended beyond the end of the intermediate fork 74 to support a load on its extended end.

The intermediate fork 74 is formed in its upper and lower surfaces with pairs of grooves 87, 88 and 89, 90 for receiving a rope extending in longitudinal direction of the fork. Referring to FIG. 24, the intermediate fork 74 is provided at its front and rear ends with advancing and retracting pulleys 91 and 93. The direction shown by an arrow in FIG. 24 is referred to as "advancing" direction in the specification. The mid portion of an advancing rope 92 extends around the advancing pulley 91 and the ends of the rope are fixed to the rear ends of the upper and lower forks 78 and 68, respectively.

The mid portion of a retracting rope 94 extends around the retracting pulley 93 and the ends of the rope are fixed to the front ends of the upper and lower forks 78 and 68, respectively. The intermediate fork 74 is formed centrally in its bottom surface with a groove

95 within which is securely fitted a rack 96 which is in mesh with a pair of pinions 98, 99 driven by a driving gear 97, whereby the intermediate and upper forks 74 and 78 are extended or retracted by the normal or reverse rotation of the pinions 98 and 99.

Any other mounting of the upper and lower bearings 73 and 83 on the upper and lower forks 78 and 68 may be employed other than those shown in the drawings.

As can be seen from FIGS. 20 to 24, the extensible and retractable fork is provided at the engagements between the intermediate fork and upper and lower forks with the plate-like bearings which are thin and of very high compression strength without using rollers. Such a bearing construction ensures that the load resistant strength and the ability which can prevent the forks from being separated can remarkably be increased and the overall height of the extensible and retractable fork can be decreased.

FIGS. 25 to 30 illustrate detecting means for detecting a loading pallet on a shelf of the multi-rack stacker system of the present invention. The casing 106 of the detecting means 105 being fixed to a frame 104 mounted on the carriage 47 of the accumulation conveyor, to which frame 104 is pivoted a lower end of a lever 107 which is formed at its mid portion with an elongated hole 108 within which is fitted an engaging pin 110 secured to the front end of a detecting shaft 109.

A rod 111 is supported by the frame 104 slidably in its longitudinal direction and is provided at its rear end with an engaging pin 112 secured thereto, which is fitted within an elongated hole 113 formed in the upper end of the lever 107. The rod 111 is further provided at its front and rear ends with front and rear actuating members 115, 117 secured thereto which actuate front and rear limit switches 114, 116 secured to the frame 104, respectively.

Referring to FIG. 26, to the rear end of the casing 106 of the detecting means 105 is connected a motor MD of which motor shaft 119 is connected through a sliding coupling 120 to the rear end of a driving shaft 118 which is centrally arranged in the casing 106 and formed at its front end with a male screw 121 on which is threadably engaged the rear end of the hollow detecting shaft 109 fitted in the casing 106 slidably in its longitudinal direction.

An inner cylinder 122 of the casing 106 is provided with a stopper 124 adapted to be engaged with a flange 123 of the detecting shaft 109 as shown in FIG. 27. A bearing 125 is rotatably fitted in place on the driving shaft 118 and provided with a switch operating finger 127 fixed thereto which extends through an elongated hole 126 of the inner cylinder 122 as shown in FIG. 28. A control switch OLM is fixed to the cylinder 122 at rear portion of the switch operating finger 127.

A pair of cylindrical holding member halves 128 abut against the bearing 125 and are urged against the same by means of springs 131 the forces of which are adjustable by adjusting screws 130 screwed in the outer portion of holding tubes 129 in opposition to the holding member halves. An adjustment of the force of the holding members 128 restraining the axial movement of the driving shaft 118 can be accomplished by the adjustment of the forces of the springs 131 by means of the adjusting screws.

FIG. 30 illustrates an electrical control circuit for the detecting means shown in FIGS. 25 to 29. When a start-

ing switch DRX is switched on, an advancing relay DF is actuated to close its contact DF-a so that the motor MD of the detecting means 105 is connected to power sources S1, S2 and thus rotated in a normal direction, with the result that the driving shaft 118 is rotated in a normal direction by means of the motor shaft 119 through the sliding coupling 120 to move forwards the detecting shaft 109 threadably engaging the male screw 121 of the driving shaft 118.

If there is no loading pallet on the shelf in front of the detecting shaft 109, the detecting shaft 109 advances until the flange 123 abuts against the front end of the casing 106 while the rear actuating member 117 switches on the rear limit switch 116 to operate a no-load indication relay DE which turns a no-load lamp on and/or operates an alarm buzzer.

The forward movement of the detecting shaft 109 is stopped when the flange 123 hits the forward end of the casing 106 as shown in FIG. 26.

However, the driving shaft 118 is still being rotated even after the forward movement of the detecting shaft 109 has been stopped so that the rotating driving shaft 118 moves backward together with the bearing 125, which is axially fitted thereto, to bring the switch operating finger 127 into contact with the control switch OLM which opens its contact OLM-1 with resulting stoppage of the motor MD and release of a meter relay ML.

When the meter relay ML is released, a contact ML-b becomes closed so that a relay PD operates to close its contact PD-a and a backward relay DR operates to close its contact DR-a and to open a contact DR-b. Accordingly, the forward relay DF is deenergized to open its contact DF-a so that the motor MD is rotated in a reverse direction to move backward the detecting shaft 109.

When the flange 123 hits the stopper 124 in its backward movement as shown in FIG. 27, the detecting shaft 109 is stopped in the position so that the rotating driving shaft 118 moves forward together with the bearing 125 to disengage the switch operating finger 127 from the control switch OLM with resulting stoppage of the motor MD and hence the driving shaft 118. When the detecting shaft 109 is in retracted position, the front actuating member 115 actuates the front limit switch 114 to operate a retracting indication relay DC whereby lighting a detecting shaft retracting indication lamp or providing other necessary indication signals.

When there is a loading pallet on the shelf in front of the detecting shaft 109, the front end of the detecting shaft 109 hits the pallet or the stock load so that the detecting shaft is stopped prior to the operation of the rear limit switch 116, with the result that the driving shaft 118 moves backward while rotating together with the bearing 125 whereby the same operations as described above are accomplished. When there are stocks, only a relay PO is operated to provide a signal indicating the presence of the stock while a relay DE is held inoperative.

In the arrangement shown in FIGS. 25 to 30, there are many advantages in that it is easy to detect the presence of a loading pallet by the use of a small detecting means which is connected to the motor MD and has a built-in detecting driving shaft, and it enables the construction to be simplified and troubles in operation to be minimized in comparison with hitherto used systems having push-button switches mounted on the top of

travelling detecting rod and cables for the switches which may be moved on a floor when travelling, and in that the motor MD is automatically controlled by means of the forward and backward movement of the detecting shaft 109 and the detection of load pallets can rapidly effected by transmission of the stroke of the detecting shaft 109 which has been exaggerated by the use of the lever 107.

FIGS. 31 and 32 illustrate an arrangement of the support members of the multi-rack stacker system in the case that shelves at the end of the system are utilized as a loading station where stocks are received from or delivered to other site such as a warehouse, a factory, etc. Referring to FIG. 31, the inner support members 2A are arranged at a closer distance to each other than that of the other inner support members 2B, these support members being arranged on both sides of the travelling line of the accumulation conveyor 7 having the fork 132 so that the distance D_1 between the endmost inner and outer support members 2A and 2C is larger than the distance D_2 between the other inner and outer support members 2B and 2D and is larger than the width D_3 of stocks or a pallet 133. Stack members 134 are spanned between the inner and outer support members. In such an arrangement, stocks 133 can be loaded or unloaded in the lateral direction, (shown by an arrow A in FIG. 31) as well as the longitudinal direction (shown by an arrow B).

Referring to FIG. 32, the endmost outer support members 2C are arranged at a wider distance to each other than that of the other outer support members 2D so that the distance D_1 between the endmost inner and outer support members 2A and 2C is larger than the distance D_2 between the other inner and outer support members 2B and 2D and than the width D_3 of stocks 133.

As can be seen from FIGS. 31 and 32, the distance D_1 between the inner and outer support members 2A and 2C is made somewhat larger than the distance D_2 between the other inner and outer support members 2B and 2D so that stocks 133 can be loaded or unloaded not only in the lateral direction but also in the longitudinal direction. Such a construction brings about many advantages in that there is no restriction of the width of the stocks for loading or unloading them in the longitudinal direction, that the cost required to manufacture the stacker system and the spaces to be occupied by the system can be decreased in comparison with the case of enlarging to D_1 the distance between all of the inner and outer support members, and that it is possible to effect a simultaneous loading or unloading of stocks in longitudinal and lateral direction on or from a plurality of stacker shelves in vertical alignment with each other.

FIG. 33 shows the relation between the support members and the accumulation conveyor of the multi-rack stacker system wherein shelves at the end of which is used as a station as mentioned above. The endmost inner support members 2A are arranged closer to each other than in the other support members 2B so that the distance D_1 between the endmost inner and outer support members 2A and 2C is larger than the distance D_2 between the other inner and outer support members 2B and 2D and the width D_3 of stocks or the loading pallet 133. Stack members 134 are spanned between the inner and outer support members. Stock 133 can be loaded or unloaded in the lateral direction (shown by

an arrow A in FIG. 33) as well as the longitudinal direction (shown by an arrow B).

The width D_4 of the portion 135 of the accumulation conveyor 7 extending beyond the endmost inner support members 2A when travelling between the multi-rack stackers in two rows is less than the width D_5 of the extensible and retractable fork 132 so that the inner support members 2A do not interfere with the travelling of the accumulation conveyor 7 even the member 10 2A are arranged closer to each other than in the other members.

As shown in FIG. 33, the distance D_1 between the inner and outer support members 2A and 2C is made somewhat larger than the distance D_2 between the other inner and outer support members 2B and 2D so that stocks 133 can be loaded or unloaded not only in the lateral direction but also in the longitudinal direction. Such a construction brings about various advantages in that there is no restriction of the width of the stocks for loading or unloading them in the longitudinal direction, that the cost required to manufacture the stacker system and the spaces to be occupied by the system can be decreased in comparison with the case of enlarging to D_1 the distance between all of the inner and outer support members, and that it is possible to effect a simultaneous loading or unloading of stocks in longitudinal and lateral directions on or from a plurality of shelves in vertical alignment with each other. Since the width D_4 of the portion 135 of the accumulation conveyor 7 extending beyond the inner support members 2A when travelling between the multi-rack stackers in two rows is less than the width D_5 of the fork on which stocks are loaded, the inner support members 2A can be arranged closer a desired distance without increasing the inner and outer distances L_1 and L_2 between the two rows of the multi-rack stackers and do not interfere with the travelling of the accumulation conveyor.

FIG. 34 is a block diagram showing fork operation controlling circuit of a conventional accumulation conveyor of a known stacker system. As shown in the figure, such a conventional system comprises an automatic control panel AC including an operation circuit and transmits following 4 instructions;

1. ascension of the carriage (CARRIAGE UP)
2. descension of the carriage (CARRIAGE DOWN)
3. right movement of the fork (FORK RIGHT)
4. left movement of the fork (FORK LEFT)

Furthermore limit switches responding to the movement of the fork are provided at the carriage and 4 signals representing following conditions are derived therefrom.

1. FC: neutral position of fork (wherein the fork not deviate either right or left)
2. FRL: extreme position of the fork (wherein the fork moved either right or left to the extremity)
3. UL: upper limit level of the carriage (the upper limit of the movement of the carriage supporting the fork at a condition when the fork is moved either right or left)
4. LL: lower limit level of the carriage (the lower limit of the movement of the carriage supporting the fork at a condition when the fork is moved either right or left)

The instructions are transmitted via a controlling circuit LC to a carriage up-down driving motor M-UD and to a fork operating motor M-F. The four position indi-

cating signals are sent to the automatic control panel AC via the controlling circuit LC and then further instructions responding to the signals will be sent from the automatic control panel AC.

As is mentioned above, since the fork operation controlling circuit of a conventional accumulation conveyor is so constructed that the four position indicating signals from the carriage are sent to the automatic control panel AC via the controlling circuit LC and that the instructions derived from the automatic control panel AC are sent through the controlling circuit LC to the carriage up-down motor M-UD and to the fork operating motor M-F, the circuit configuration of the automatic control panel AC and the controlling circuit LC becomes complicated. Therefore such conventional system has further drawbacks in the difficulty of the maintenance and inspection of the device and as the consequence for high equipment cost.

FIG. 35 is a block diagram of a fork controlling circuit and FIG. 36 is a circuit diagram of fork and carriage controlling circuit made in accordance with the present invention which mitigates abovementioned disadvantages of the conventional system. As generally shown in FIG. 35 in the system of the present invention, the automatic control panel AC including operational circuit therein sends out following four instructions to the controlling circuit LC.

1. shipping a load (OUT)
2. storing a load (IN)
3. right movement of the fork (FORK RIGHT)
4. left movement of the fork (FORK LEFT)

As will be explained more fully hereinafter in the present system, the carriage of the conveyor, and the extensible and retractable fork are operated only by the above instructions and the position indicating signals from the fork are not required to be sent back to the automatic control panel AC via the controlling circuit LC.

More detailed explanation for the operation of the fork and carriage driving circuit will be given by referring to FIG. 36.

In the FIG. 36, each contact in a contact group ACR shown left top portion is closed by the instruction of the automatic control panel AC. Ra and Rb denote contacts of relay R, which operates when the fork is moved to the right, and La and Lb denote contacts of relay L, which operates when the fork is moved to the left. Contacts Pa and Pb of a relay P operate when a pallet is to be shipped out, and contacts Da and Db of a relay D operate when a pallet is stored in.

Contacts ULa and ULb operate when the carriage reaches upper level, contacts LLa and LLb operate when the carriage reaches lower level, contacts FRa, FRb and FLa, FLb operate when the fork reaches extreme right and extreme left respectively, and contacts FCa, FCb operate when the fork is in neutral position. The relays R and L are so arranged as to interlock each other via contact Lb and Rb operated by relays L and R respectively in order that they do not operate simultaneously. Also the relays P and D are interlocked each other by the contacts Db and Pb operated by relays D and P.

The operation of the fork and the carriage will be explained by taking an example when a stock load pallet is shipped from right shelf of the stacker system.

By a shipment instruction sent from the automatic control panel AC, a contact PX in the contact group

ACR closes and thus relay P is energized and closes its contact Pa and opens its contact Pb. Then by an instruction of "FORK RIGHT" the contact RX is closed so that relay R is energized and closes its contact Ra and opens its contact Rb. By this circuit, the fork and carriage operate in a manner and sequence set forth below. An electric current flows from a source terminal R1(200V) to an instruction terminal "DOWN CARRIAGE" through a circuit:

10 R1(200V) — $\overline{1}$ — $\overline{2}$ — $\overline{3}$ — $\overline{4}$ — Ra — $\overline{5}$ — Pa — $\overline{6}$
— — FCa(closing when shipping) — LLD —
"DOWN CARRIAGE" —

By this current the carriage descends and at its lower extreme position the contacts LLa and LLb — are operated to close and to open, respectively. By the opening of the contact LLb the "DOWN CARRIAGE" circuit is interrupted at . . . $\overline{6}$ -FCa — LLb — "DOWN CARRIAGE."

By the closure of the contact LLa, a current flows to a terminal "FORK RIGHT" via a circuit, . . . — $\overline{7}$ — LLa — FRb — FLb — Ra — $\overline{17}$ — "FORK RIGHT" so that the fork is moved to the right.

When the fork reaches the right extremity, a limit switch is operated so that the contact FRb is opened and the fork driving current is thus interrupted. At the same time by the closure of contact FRa in a circuit via 25 $\overline{8}$ — FRa — ULb, the current flows via a circuit . . . $\overline{8}$ — FRa — ULb — "UP CARRIAGE" to the terminal "UP CARRIAGE." By this current the carriage ascends together with the fork.

When the fork reaches upper limit level, the contact ULb opens to interrupt the fork current. At the same time by the closure of contact ULa in a circuit $\overline{8}$ — ULa — FCb — Ra, the current now flows to a terminal 35 "FORK LEFT" via . . . $\overline{8}$ — ULa — FCb — Ra — "FORK LEFT" and the fork moves toward its neutral position carrying the pallet load.

At the neutral point, the fork opens contact FCb thus the fork and carriage can complete one cycle operation.

As can be seen by the operation, the position indication signals of the fork are treated independently from the automatic control panel AC and is used in the fork driving circuit forming a part of the controlling circuit LC. When the fork returns to the neutral point, an operation completion signal is sent through controlling circuit LC to the automatic control panel AC by an operation of a limit switch, which then responds to the completion signal in sending desired succeeding signal, such as "RETURN CONVEYOR," "DOWN CARRIAGE," etc. so that the accumulation conveyor may return to a pallet-loading station provided at an extremity of the multi-rack stacker shelves where it may be unloaded.

55 When the fork is to be moved toward the left shelf to bring out a pallet stored therein a substantially same operation is made by closing a contact LX instead of the contact RX in the contact group ACR.

As has been explained by referring to FIGS. 35 and 60 36, the multi-rack stacker system according to the present invention comprises an automatic control panel AC including an inside operation circuit therein and a controlling circuit LC, and also a fork controlling circuit including a circuit to respond to the instructions sent from the automatic control panel AC, such as "UP CARRIAGE," "DOWN CARRIAGE," "FORK RIGHT" and "FORK LEFT" and a circuit for control-

ling one cycle operation of the fork started by an operation of a relay contact included in the above circuit.

In the stacker system according to the present invention, there is no need to send back signals derived from the limit switches provided at the carriage to the automatic control panel AC via the controlling circuit LC such as in the conventional system so that the fork and the carriage can be controlled only by the above four instruction signals originated from the automatic control panel AC and hence the construction of the automatic control panel AC and the carriage controlling circuit LC can be made very simple. This provides further advantages in that the maintenance and inspection of the equipment become easier and that the installation cost might be decreased.

FIG. 37 shows an outline of a fork extending and retracting controlling circuit of a conventional multi-rack stacker system. In FIG. 37, L1 and L2 show a pair of supply terminals, K is a movable contact of a switch S, SR and SL are stationary contacts of the switch S, FR is a limit switch which operates to open when the fork is in the right extremity, FL is a limit switch operating to open when the fork is in the left extremity, FCR and FCL are limit switches operating to open when the fork is at the neutral position, QMLF and QMRF are contacts operating to open at energization of field coils MLF and MRF of the driving motor, respectively, and to interlock the coils MRF and MLF each other, PR and PL are push-buttons.

The operation of the controlling circuit shown in FIG. 37 will be explained.

If the fork is to be driven to either direction (for instance to the right direction), at first the movable contact K of the switch S is switched to contact the stationary contact SR and the push-button PR is depressed. Then a current flows via a circuit L — K — SR — FR — PR — QMLF — MRF — L2, so that the motor starts to rotate in one direction (right rotation).

By the right movement of the fork from its neutral position, the limit switch FCR closes and keeps the above driving circuit even after the opening of the push-button contact PR and the limit switch FR operates to open the circuit to stop the fork at arriving to the right extremity.

By the switching of the movable contact K to another stationary contact SL, the current flows through coil MLF via then closing limit switch FL, contact FCR and the interlock contact QMRF, and the motor is rotated in the reverse direction (left rotation) so as to return the fork to the neutral position and stop the fork at a condition of opening the limit switch FCR.

If the fork is to be moved to the left, the lower part of the circuit shown in FIG. 37 operates in the same manner.

In such conventional fork controlling circuit, however, there has been inconveniences in that the push-button PR or PL must be held by hand until the operation of the limit switch FCR or RCL by the movement of the fork from its neutral position so that the controlling is troublesome.

FIG. 38 shows an improved circuit diagram of the fork controlling circuit of the multi-rack stacker system according to the present invention, which mitigates the aforementioned disadvantages. In this improved fork controlling circuit, the limit switches FCR and FCL, which are opened at the neutral position of the fork, are connected in parallel with timer contacts PR and

RL, which are opened by timers TR and TL, respectively. The timers TR and TL are connected in parallel with circuits RR-QMLF-MRF and RL-QMRF-MLF, respectively. The rest portion of the circuit is nearly the same as the conventional circuit shown in FIG. 37 so that a duplicate explanation need not be made.

In the fork controlling circuit as shown in FIG. 38, if the fork is to be moved to the right, at first the movable contact K of the change over switch is switched to fixed contact SR to cause to flow a current via a circuit — L1 — K — SR — FR — TR — L2 — so that the timer TR is energized to operate and to close contact RR. Then a current flows through — L1 — K — SR — FR — RR — QMLF — MRF — L2 to operate the motor and thus the fork moves to the right from the neutral position so that the limit switch FCR closes the contact.

If the fork is to be moved to the left from the neutral position, the lower part of the circuit shown in FIG. 38 is to be operated.

Said timers TR and TL hold contacts RR and RL for two seconds and release them thereafter. In the embodiment shown in FIG. 38 timers are used to provide slow release function for the contacts RR and LL, but it should be noted that this is merely an example and any electrical or mechanical device to provide such slow time release function can be used.

According to the present invention, the fork controlling circuit of the multi-rack stacker system comprises a switch-over contact, a limit switch indicating fork extremity, motor interlock switch and field coil of the motor connected in series, a timer release contact RR or RL operating to open circuit after a certain predetermined time is connected in parallel with limit switch FCR or FCL or for both switches FCR and FCL so that the push-button switch need not be kept depressed at the time of moving the fork as in the case of the conventional controlling circuit. Furthermore there is no need to provide push-buttons at the controlling panel thus controlling practice can be simplified and hence decreases the operator's load.

FIG. 39 shows a block diagram of a conventional control circuit for the accumulation conveyor of a conventional multi-rack stacker system. The operation of such known circuit by taking an example of storing a load will be explained. At first a particular location which may be termed as an address of the pallet loading station is given.

Address of the rack wherein the pallet is to be stored is memorized in the instruction circuit OC by means of a storage-address card. If a start instruction push-button in the automatic control panel is depressed, shift register SR sends out an instruction to a detector so that the detector operates to check the existence of the pallet in the station.

When the existence of the pallet in the station is confirmed, the shift register SR transmits an instruction signal at the receipt of the confirming signal and carries out the pallet. The shift register SR upon receipt of a loading completion signal transmits a shelf indicating signal SF. By this shelf indicating signal SF, a shelf indicating instruction circuit OC and a shelf position detecting circuit PDC are connected to an operation circuit CC, wherein the position of the conveyor and the allocated position of shelf are compared with each other so that the conveyor is moved forward and upward under control of the operation circuit CC until the allocated binary number to the desired shelf loca-

tion coincides with the binary number representing the conveyor position. When the above two position indicating signals coincide with each other, the conveyor is stopped and it delivers a signal to the shift register SR by which the shift register SR delivers an instruction signal for instructing detection operation to the operation circuit CC which in turn energizes controlling circuit LC. The controlling circuit LC checks the existence of pallet at the shelf location and if it confirms that the allocated shelf location is vacant, a confirming signal is sent out. By the vacant confirming signal the shift register SR transmits a fork driving signal to the operation circuit by which signal the fork moves to unload the pallet in the allocated storing position. Upon completion of the storing, the conveyor stands still in the position and enters in stand-by condition in which it is ready for receiving further instruction.

In order to return the conveyor back to the station, back station instruction is sent from the shift register SR to an instruction circuit OCS memorizing station address, and by this instruction the instruction circuit OCS is connected to the operation circuit CC in which the conveyor address is compared with the station address and by the result of the operation the conveyor is driven to move until its address coincides with the address of the loading station whereat the conveyor is stopped.

As can be seen from the abovementioned explanation in the conventional controlling system, the accumulation conveyor stands still at the unloaded shelf location and when the conveyor is desired to return back to the station the conveyor location must be compared with the station address in the operation circuit and by the result of this operation the conveyor is moved. Moreover, the operation circuit must make subtraction operation so that the construction of such subtraction operation circuit becomes complicated.

FIGS. 40 to 42 show automatic return circuit of the accumulation conveyor according to the present invention which mitigates the aforementioned disadvantages. According to the circuit of the present invention, the instruction circuit OCS producing station location signal in the conventional controlling circuit can be dispensed with and the operation circuit can be made of simple addition circuits only and hence the complicated subtraction operation circuit need not be employed. Accordingly in the controlling circuit of the present invention, the returning instruction of the shift register is directly connected to a driving circuit LC. Therefore, although the conveyor position detecting circuit PDC operates in the same manner with the conventional circuit until carriage of the accumulation conveyor reaches designated shelf location, but the detecting circuit PDC is no longer needed in the carriage controlling operation thereafter.

The instruction system diagram is shown in FIG. 42. At arrival of the accumulation conveyor to a designated location, the circuit operates to detect pallet and to operate the fork as same as the conventional circuit. Upon receipt of fork operation completion signal to the shift register SR, the shift register SR delivers an instruction signal S to the accumulation conveyor to return to the station. In the conventional system as shown in FIG. 39, such instruction signal S sent from the shift register operates an instruction circuit OCS memorizing the station address and a position detecting circuit PDC to connect to the controlling circuit CC. Contrary

thereto by constructing the circuit as shown in FIG. 42 according to the present invention, the circuit can be simplified and the shift register SR transmits backward conveyor or down carriage instruction to the controlling circuit LC and the accumulation conveyor returns to the station by means of limit switches provided at the carriage to stop the conveyor at the station.

The operation of the controlling circuit as shown in FIG. 40 will be explained. In the drawing, L1 and L2 designate supply source terminals, MU is an upward driving coil of the motor, MD is a downward driving coil of the motor, MF is a forward driving coil, MR is a backward driving coil of the motor. The contacts having denotation with above coils are the contacts operating at energization of the respective coil. ARa is a contact operating from an instruction of the shift register, LGHb is a lower limit switch operating when the carriage is at the same level with the station, LGTb is a switch operating at extreme backward position of the carriage on the conveyor.

Operation of the controlling circuit shown in FIG. 40 will be explained.

At completion of unloading the unloading completion signal is sent from the carriage. In accordance with the completion signal an instruction is sent from the shift register SR to a contact ARa of the controlling circuit LC thus the contact ARa closes. Upon closure of the contact ARa, the downward driving coil MD is energized and thus the carriage is moved down. At the same time the backward driving coil MD is energized through another operating contact ARa and the accumulation conveyor is moved backward. If the down movement of the carriage is earlier and the carriage reached the station level, the carriage stops at the level and the accumulation conveyor continues backward movement and stops at the loading station by an operation of the switch LGTb. If the backward movement of the accumulation conveyor is earlier, the limit switch LGTb operates at its extreme backward position to stop the accumulation conveyor and the carriage continues the down movement and then stops at the loading station by the operation of contact LGHb. Coils MD, MU and coils MF, MR are interlocked with each other by another one of the pair.

In accordance with the system of the present invention, the accumulation conveyor equipped with an automatic control panel having an operation circuit and a controlling circuit having automatic return function can be made in a very simple construction mainly by the following reason that the operation circuit can be made by addition circuit only, that the carriage is equipped with signalling means so that to send out working completion signal, that the automatic control panel delivers an instruction to return to the station based on the working completion signal directly to the controlling circuit without employing an operation circuit, and that the carriage and the accumulation conveyor return to the station automatically with the aid of limit switches provided at the controlling circuit and the carriage. The present system affords a great advantage in that the operation circuit becomes much simpler since it is constructed from the addition circuits only, that the carriage and the accumulation conveyor can return to the station automatically always after completion of unloading of the pallet by sending backward and downward instructions from the shift register SR directly to the controlling circuit and by controlling

the driving motor by a controlling circuit including a limit switch provided at the carriage.

FIGS. 43 and 44 show block diagram and circuit diagram of the automatic control panel and the controlling circuit of a conventional accumulation conveyor. As shown in FIG. 43, the automatic control panel AC including an operation circuit and the carriage control circuit LC are constructed in separate units designated B and A, respectively, and in the latter unit the carriage ML is included. The automatic control panel AC is provided with a test device, but the test device can test the function of the automatic control panel AC including the operation circuit only and the test of the carriage ML and the controlling circuit LC are not tested. Namely, in the conventional system there have not provided equivalent switches corresponding to contacts LS1, LS2, . . . of the limit switches provided at the carriage so that the test equipment cannot make test for the controlling circuit LC and the carriage ML.

FIGS. 47 to 47 show block diagram and circuit diagrams of the controlling circuit of the accumulation conveyor according to the invention, which includes a test equipment for mitigating abovementioned disadvantage of the prior system. As shown in FIG. 45, the automatic control panel AC, the controlling circuit LC and the carriage ML are installed in one unit C so that the limit switches at the carriage can be tested. In the system of the present invention as shown in FIGS. 46 and 47, a test contact TEST-1 is inserted between the driving coil RL1 and a limit switch contact LS1 of the upper level limiting circuit UL which operates at extreme upper level of the carriage moving along the vertical frame of the accumulation conveyor. Furthermore a series circuit of a switch SW1 and a test contact TEST-1' is connected in parallel with said circuit consists of the contact LS1 and contact TEST-1, wherein the contact TEST-1 and TEST-1' are ganged to operate simultaneously as is more clearly shown in FIG. 47.

The switches SW1, SW2, SW3 . . . are the switches provided on a test panel of the test equipment. At the time of the testing of the system the test panel is connected to the controlling circuit LC by means of cable, etc. as shown in FIG. 47, wherein the portions P, Q and P', Q' are the suitable connecting means such as an electric cable connector.

Switch SWT of the test equipment shown in FIG. 47 is used at the testing and which energizes coil CT to interrupt the driving motor circuit of the carriage ML. When the upper limit circuit UL of the extending and retracting fork is to be tested, at first the test contact TEST-1 is opened and the test contact TEST-1' is closed and then by closing switch SW1, the upper level limiting coil RL1 can be tested for its operation.

Corresponding circuit is provided for each of the fork lower limit circuit LL, the fork neutral position indicating circuit FC, the fork end operating circuit FRL with abovementioned upper limit circuit RL, these circuits can be tested in the same manner.

FIG. 48 shows one possible alternative of the controlling circuit shown in FIG. 46. This circuit operates under control of the dc supply source and the circuit formed by TEST-1, TEST-1' . . . had been replaced by diodes D1, D1' . . . and at the time of testing a current is flown through a terminal L1'. By using such diode circuit, the circuit trouble can be decreased and the circuit can be constructed economically.

The accumulation conveyor system according to the present invention comprising the carriage and the controlling circuit including test panel device and operation circuit as shown in FIGS. 45 to 48, is so constructed that the controlling circuit includes a testing circuit and switches to connect the test circuit by its test switches, and that a test device is provided separately from the automatic controlling panel which affords advantages that the device can be equipped one unit C as shown in FIG. 45, that the plurality of units can be tested by using a separately formed test device so that there is no need to prepare an installed type test device for each automatic controlling panel of the accumulation conveyor. Accordingly, it is possible to decrease the installation cost in case of a plurality of multi-rack stacker systems are used in one warehouse, etc. Also the test device can test the control circuit or the carriage in a very simple manner which was not possible in the conventional system.

In accordance with the present invention, the multi-rack stacker system can be installed in a very simple manner to keep accurate predetermined interval between the two parallel multi-rack shelves 1, since the upper portion and the lower portion of the system are fixedly connected by a plurality of longitudinal upper members 4 and lower members 5, respectively, in a detachable manner for keeping the predetermined interval. Furthermore, by simply mounting upper rail 6 and lower rail 8 at the center portion of each of the upper connecting member and the lower connecting member 5, said upper and lower rails 6 and 8 are mounted accurately along the center of the multi-rack stacker system and hence the alignment between the upper portion and the lower portion of the accumulation conveyor with upper and lower rails can be made very easily and accurately.

According to the system of the present invention, it is possible to make field assembly for the parts prefabricated mass-productive manner in a factory so that relative dimension of each constructive part of the stacker system can be made with high accuracy and also high accurate assembly is possible. The stacker system can easily be reinstalled after detaching to the parts. The system can be installed very simply, it may be used as a moving or a temporary storage store. Accordingly, the multi-rack stacker system equipped with a vertical accumulation conveyor can be installed with ease and accurate. Moreover, in the system of the present invention, each support member 2 is provided at its lower end a universally movable and height adjustable base 3 so that the system can be installed even on a floor 14 including certain unevenness or some inclination in a manner that each base 3 stably sits on the floor 14 over a wide area and such a situation in which a part of such support member is unseated to cause unbalance or partially deformation of the multi-rack stacker shelves can be prevented and also a case of causing concentrated load onto a particular support member may be avoided.

Various modifications and alternatives are possible without departing from the scope of the present invention.

We claim:

1. A multi-rack stacker system equipped with an accumulation conveyor comprising multi-rack stacker shelves arranged in two rows and at lower portion of each support member thereof a base is fixed in a man-

ner height adjustable and universally movable in any direction, the multi-rack stacker shelves are provided at the upper and lower ends with a number of upper connecting members and a number of lower connecting members detachably arranged spaced apart at an interval in the longitudinal direction of the multi-rack stacker shelves, upper end portion of the accumulation conveyor is supported in freely running manner by an upper rail detachably fixed at the center of the upper connecting members, and lower end portion of the accumulation conveyor is supported in a freely running manner by a lower rail detachably fixed at the center of the lower connecting members.

2. A multi-rack stacker system as set forth in claim 1, wherein said upper rail (6) is I-shaped in cross-section, on the lower flange (26) of which are arranged upper rollers (27) of the upper end of said accumulation conveyor (7) one at each side of the web of the upper rail, and said lower rail (8) is inwardly flanged, open bottomed channel-shaped in cross-section and is firmly fixed to the lower connecting members (5) by means of clamp members (28) and screw threaded members (29) and lower rollers (30) are arranged one at each side of the lower rail (8) in guiding contact with the vertical webs of the rail (8) and are rotatably supported on the lower end of the accumulation conveyor (7) by vertical shafts (31).

3. A multi-rack stacker system as set forth in claim 1, wherein said base (3) is provided with height adjusting means (17) comprising a male screw 18 adapted to be screwed into a female screw threaded fitting (15) fixed to the lower end of said each support member (2) and a nut (16) adapted to be rotated by a wrench or the like rotary tool.

4. A multi-rack stacker system as set forth in claim 3, wherein said base (3) is hemispherical which is provided at its periphery with a flange (20) and is formed at its center with an opening loosely receiving the smaller diameter portion (19) of said height adjusting means (17) such that said base (3) is universally movable about the portion (19) in any direction.

5. A multi-rack stacker system as set forth in claim 3, wherein said base (3) is hemispherical which is formed at its center with a hemispherical cavity (32) receiving a hemispherical head (33) of said height adjusting means (17) abutting thereagainst, said base (3) being provided with a ring (34) fixed to the outer end of said cavity for preventing the loss of the base assembly.

6. A multi-rack stacker system as set forth in claim 1, wherein said accumulation conveyor (7) comprises a carriage (47) lifting along guide rails (38) mounted on longitudinal frames (35) each consisting of a box-shaped main body (36) elongated in the carriage travelling direction and reinforcing members (39) of box-shaped in cross-section arranged on and fixed to the end of the main body (36) opposite to said guide rail (38), said members (39) located one on each side of said main body (36).

7. A multi-rack stacker system as set forth in claim 6, wherein a reinforcing plate (40) in said main body and webs (41) of the member (39) are made of a single plate, and an end plate (42) and webs (43) of the member (39) on the end of the main body opposite to the guide rail (38) are also made of a single plate, the metal plates of the longitudinal frame (35) being connected with each other by means of welding, and wherein in

the spaces within the main body (36) and reinforcing member (39) are accommodated reinforcing spacer plates (44, 45, 46) fixed by welding at intervals along a longitudinal direction of the frame (35).

5 8. A multi-rack stacker system as set forth in claim 6, wherein webs (49) connecting end plates (37, 42) of the main body (36) are made of single plates, respectively, between which, if desired, a reinforcing plate (50) is secured to the webs (49) intermediate the ends thereof.

15 9. A multi-rack stacker system as set forth in claim 6, wherein an end plate (42) of the main body (36) and webs (43) of the reinforcing member (39) are formed in one plate integral with each other.

20 10. A multi-rack stacker system as set forth in claim 1, wherein a switch support plate (51) is pivotally mounted at its end on said carriage (47) of the accumulation conveyor (70) by means (7) a horizontal pivot axis (52), with the other end of which plate is engaged a spring (58) urging the plate toward a striker rail (61) of said conveyor (7), on the outer surface of which support plate (51) are mounted limit switches (60) and guide means (59), and to said striker rail (61) is fixed a striker support plate (63) to which are fixed strikers (66) actuating said switches (60) and guide member (67) in supportingly contact with said guide means (59).

25 11. A multi-rack stacker system as set forth in claim 10, wherein to said carriage (47) is fixed support members (53), through each of which passes a screw threaded portion 55 of a support rod 54 having an adjusting nut 56, said spring (58) being coiled about said support rod (54) and adapted to be compressed between the upper end of the switch support plate (51) and the support member (53), thereby adjusting the force of the spring (58).

30 12. A multi-rack stacker system as set forth in claim 10, wherein a roller is used as guide means (59).

35 13. A multi-rack stacker system as set forth in claim 10, wherein a slide shoe is used as guide means (59).

40 14. A multi-rack stacker system as set forth in claim 10, wherein a roller is used as a guide member (67) and a rod-like member is used as guide means (59).

45 15. A multi-rack stacker system as set forth in claim 10, wherein said striker rail (61) is formed with a number of mounting apertures (62) in a row at a short distance interval, and said striker support plate (63) are formed with vertically elongated holes (64) which serve to secure said striker support plates (63) to said striker rail (61) adjustably in height.

50 16. A multi-rack stacker system as set forth in claim 1, wherein said accumulation conveyor (7) is provided with an extensible and retractable fork mounted thereon, including a lower fork (68), an upper fork (78) and an intermediate fork (74), and said extensible and retractable fork comprises lower flat plate-like restraining bearings (73) between the mid portion of said lower fork (68) and said intermediate fork (74) for preventing said intermediate fork from raising away from said lower fork, flat plate-like bearings (76) at the contact portion between the end of said lower fork and said intermediate fork for supporting load, upper flat plate-like restraining bearings (83) between the mid portion of said intermediate fork and said upper fork for preventing said upper fork from raising away from the intermediate fork, and flat plate-like bearings (85)

55 60 65 66 67 68 73 76 83 85

at the contact portion between the end of said intermediate fork and said upper fork for supporting load.

17. A multi-rack stacker system as set forth in claim 16, wherein said fork further comprises advancing and retracting pulleys (91, 93) provided at the front and rear ends of said intermediate fork (74), an advancing rope (92) extending around the advancing pulley 91, the end of which are fixed to the rear ends of the upper and lower forks (78, 68), respectively, and a retracting rope (94) extending around the retracting pulley (93), the ends of which are fixed to the front ends of the upper and lower forks (78, 68).

18. A multi-rack stacker system as set forth in claim 1, wherein said system is provided with detecting means (105) for detecting loading pallets, the casing (106) of which is fixed to the carriage 47 of the system, to the rear end of which casing (106) is fixed a motor (MD) of which shaft (119) is connected through a sliding coupling (120) to the rear end of the driving shaft (118) formed at its front end with a male screw (121) on which is threadably engaged a detecting shaft (109) slidably fitted in said casing (106) and a bearing (125) is rotatably fitted in place on said driving shaft (118), against the outer surface of which bearing (125) abut holding members (128), said bearing (125) being provided with a switch operating finger (127) fixed thereto in opposition to a control switch OLM controlling the operation of said motor (MD).

19. A multi-rack stacker system as set forth in claim 18, wherein said holding members (128) for said bearing (125) are urged against said bearing (125) by means of springs (131) the force of which are adjustable by adjusting screws (130) screwed in the outer portion of holding tubes (129) in opposition to the holding members, thereby adjusting the force of the holding members (128) restraining the axial movement of the driving shaft (118).

20. A multi-rack stacker system as set forth in claim 1, wherein a distance (D₁) between the endmost inner and outer support members (2A, 2C) of said shelves (1) is larger than a distance (D₂) between the other inner and outer support members (2B, 2D), thereby stocks (133) can be loaded or unloaded in the longitudinal direction as well as the lateral direction.

21. A multi-rack stacker system as set forth in claim 1, wherein the endmost outer support members (2C) of said shelves (1) are arranged at a wider distance to each other than that of the other outer support members (2D) so that the distance (D₁) between the endmost inner and outer support members (2A, 2C) is larger than the distance (D₂) between the other inner and outer support members (2B, 2D) and than the width (D₃) of the stocks (133).

22. A multi-rack stacker system as set forth in claim 1, wherein the endmost inner support members (2A) are arranged closer to each other than in the other sup-

port members (2B) so that the distance (D₁) between the endmost inner and outer support members (2A, 2C) is larger than the distance D₂ between the other inner and outer support members (2B, 2D), thereby stocks (133) can be loaded or unloaded in the longitudinal direction as well as the lateral direction, and the width (D₄) of the portion (135) of the accumulation conveyor (7) passing through between the endmost inner support members (2A) is less than the width (D₅) of the fork (132).

23. A multi-rack stacker system as set forth in claim 1, wherein said accumulation conveyor (7) including an automatic control panel (AC) having an operation circuit, a controlling circuit and carriage (47), said controlling circuit comprises a fork controlling circuit consisting of a first circuit responsive to instructions of "UP CARRIAGE," "DOWN CARRIAGE," "FORK RIGHT" and "FORK LEFT" from said automatic control panel and a second circuit for controlling one cycle operation of said fork started by an operation of a relay contact included in said first circuit.

24. A multi-rack stacker system as set forth in claim 1, wherein said accumulation conveyor (7) including a fork controlling circuit, said circuit comprises a switch-over contact, a limit switch indicating fork extremity, a limit switch indicating the predetermined positions of said fork, motor interlock switch and field coil of the motor connected in series, and further comprises a timer release contact (RR) connected in parallel with said limit switch (FC) indicating the predetermined positions of said fork, said contact (RR) being adapted to be opened by a timing device.

25. A multi-rack stacker system as set forth in claim 1, wherein said accumulation conveyor (7) including an automatic control panel having an operation circuit, a controlling circuit and a carriage, said operation circuit is made of addition circuit only, and said carriage is provided with signalling means to send out working completion signal which provides an instruction from said automatic control panel to a station, which instruction is directly given to said controlling circuit without using any operation circuit, thereby said carriage and accumulation conveyor return to the station automatically with the aid of limit switches included in the controlling circuit and the carriage.

26. A multi-rack stacker system as set forth in claim 1, wherein said accumulation conveyor including an automatic control panel having test panel device and operation circuit, a controlling circuit and a carriage, said accumulation conveyor comprises accumulation conveyor control means having portions adapted to be connected with a testing circuit and switches provided on said test panel device, and a test device separate from said automatic control panel.
